2,541,051

APPARATUS FOR AUTOMATIC PRODUCTION
OF MUSICJohn M. Hanert, Park Ridge, Ill., assignor to
Hammond Instrument Company, Chicago, Ill.,
a corporation of Delaware

Application November 1, 1945, Serial No. 626,150

28 Claims. (Cl. 84—105)

1

My invention relates generally to apparatus for the automatic production of music.

In general the object of the invention is to provide apparatus by which musical scores may be translated into musical renditions suitable for production as sound or as a signal for recording purposes, without the employment of musicians in any way whatsoever. In other words, the invention contemplates that a composer or arranger may, using the apparatus of the invention, score the musical composition, whereupon the music will be produced automatically by the apparatus with all the variations usually present in orchestral renditions of music, such variations being in pitch and tone quality, in volume, in accent of individual notes, in tempo, and in tone intensity envelopes.

While some features of the invention are applicable to the control of conventional mechanical and electrical musical instruments, the invention is herein illustrated as applied to the control of electronic musical instruments and apparatus.

It is thus among the objects of the invention to provide:

1. An apparatus whereby a suitable record marked upon paper or the like and representing all of the characteristics of tone quality, of tone intensity envelope, accent, tempo and the like may be automatically translated into electrical signals representative of an orchestral rendition of a musical composition;

2. An improved means for producing a record of the musical score;

3. An improved means for controlling the output of a plurality of electrical musical instruments;

4. Improved means for detecting and translating a musical score marked on paper into signals utilizable for the control of musical instruments;

5. An improved apparatus in which one record may be used to control the pitch, accent and the like whereas another marked record is selectively operated by the first marked record to secure predetermined changes in the instrumentation, vibrato and volume;

6. An improved apparatus for securing a multiplicity of predetermined changes in tone quality, tone intensity envelope, accent, tempo, vibrato and the like by means of a single mark on the main controlling record;

7. An improved record of paper or similar material composed of a plurality of cards overlapping in a shingle-like manner so as to form a long record in which shrinkage of the paper or

2

other material does not have any appreciable effect;

8. A series of overlapping tables for supporting the record whereby leveling of the tables is facilitated;

9. An improved notation card having imprinted thereon a set of timing or rhythm markings and a set of note position markings extending perpendicular to the timing or rhythm markings;

10. An improved scanner mechanism operating in timed sequence for sensing the musical notations marked upon the record cards;

11. An improved scanning mechanism which does not injure, obliterate or otherwise render ineffective the scored musical markings even though used repeatedly;

12. An improved electrical transducer for converting the scanned markings into corresponding changes in electrical current flowing through an electronic load circuit;

13. An improved alternating current generating system producing musical tone frequencies with means for transmitting, collecting, and controlling the intensity envelope characteristics of the tones by a direct current determined by a scanning mechanism;

14. An improved orchestral registration and control table having means for moving it in response to score markings;

15. An instrumentality of the above mentioned type in which the overall expression in the output is controlled by markings on a record; and

16. An improved record scanning mechanism in which the speed of scanning is controlled by markings on the record being scanned.

Other objects will appear from the following description, reference being had to the accompanying drawings in which:

Figure 1 is a schematic diagram showing the relationship of the various components of the complete apparatus;

Figures 2, 3, 4 and 5 are schematic diagrams of various forms of scanning circuits and associated elements;

Figure 6 is a schematic diagram of the circuit employed to operate the solenoid of the instrumentation sequence table under the control of markings on the record;

Figures 7 and 8 are schematic diagrams of the circuits and associated elements of two modified forms of scanning apparatus;

Figure 9 is a plan view of the time sequence or record supporting table;

Figure 10 is a side elevational view of said table;

Figure 11 is an enlarged fragmentary sectional view taken on the line 11—11 of Fig. 9 and showing one of the record card locating pins;

Figure 22 is a schematic diagram showing a modification of the means for sensing card notations.

General description

It is customary practice in the production of orchestral music for the composer to write the original score, possibly with only infrequent notations as to the instrumentation to be employed, and in some instances without any instrumentation. This score is then used as a guide by the arranger (who may also be the composer) and the scores for the various instruments of the orchestra are written, usually a separate score for each instrument of the orchestra by which the composition is to be rendered. In music to be arranged for an orchestra of a large number of pieces this is a tedious process, while it nevertheless requires a high degree of artistry and skill.

Thereafter the "arrangements" of the musical compositions are utilized by the members of the orchestra for rehearsal and final rendition of the composition. The composer ultimately usually has but slight control over the instrumentation employed by the orchestra and it is only after these tedious and time consuming steps have been taken and the orchestra ultimately renders the composition that the composer can actually audition his composition played in the manner the public may be expected to hear it.

Especially in the making of phonographic or similar sound recordings frequent rehearsals are necessary in order to assure that the recording made will accord with reasonable fidelity with the ideas of the composer and orchestra conductor as to how the composition should be interpreted and rendered. In actual practice it is seldom that a recording represents the closeness to perfection which is anticipated by the composer and conductor, since in each rendition by an orchestra

5 a fault or imperfection in technique by one or more of the musicians is likely to manifest itself. In endeavoring to correct the faults of a previous rendition, the conductor is likely to find that other faults have insinuated themselves.

6 The difficulties inherent in the orchestral production of a composition may be compared to those which would confront an artist who found it necessary in painting a picture to destroy the complete or partially complete picture he was painting every time he became dissatisfied with any slight detail of the picture. The painter is not subject to such stringent regulation but instead merely repaints such minor portion of the whole picture which does not represent the subject being painted sufficiently accurately to meet his artistic approval. In endeavoring to make a musical phonographic recording, the artist conductor does not have this opportunity to erase and correct slight blemishes in details but instead must rehearse the orchestra repeatedly until the complete composition can be rendered in reasonable compliance with his artistic concept of how the rendition should sound.

7 In the method and apparatus of this invention the composer, arranger, or conductor has at his command means for controlling the quality of each note, its intensity, intensity envelope, the degree of accent, duration, and tempo without necessarily affecting any other note or tone of the composition. He thus has under his control, within the limitations imposed by the apparatus as a whole, facilities for producing, under his sole control, any of a substantially infinite variety of renditions of a composition.

8 In actual practice it has been found that it is not ordinarily practical to provide too many separate instrumentalities for producing the tone frequencies and controlling their various characteristics such as quality, tone intensity envelopes and the like, since in the music ultimately produced, even the most trained musician cannot detect minor changes in these qualities of the music. Since most auditory as well as other perceptions are governed by the Weber-Fechner law that the stimulus must increase in geometrical steps to cause noticeable differences in sensation, the number of steps of gradation in volume, degree of vibrato, change in intensity envelope, and changes in tone quality, need not be very great.

9 The apparatus includes means for supporting marked notation or record cards, comprising a long sectional table having rails along its longitudinal edges for a motor driven scanning carriage. The record notation cards have suitable perforations cooperating with locating pins projecting upwardly from the table, the cards being laid on the table in overlapping shingle fashion. The cards may be of any suitable size, one practical size being approximately 11" x 12". The cards bear suitable markings indicating the measures of the music to be scored thereon, each measure being divided into quarter tones, 8th tone intervals as well as making provision for triplets aggregating a quarter tone. In aggregate length there are sufficient cards (39) to score a composition of at least 96 measures. For convenience there are three cards side by side to accommodate the usual number of required varieties in orchestral control. In addition, there are provided two instrumentation control cards which are located on a separate instrumentation table and cooperate with a separate scanning apparatus.

10 In scoring a composition to be produced the composed or arranger may suitably mark cards in

a pack, and by marking the cards to indicate the order in which they are to be placed upon the tables, they may be initially scored by the composer or arranger at his home or desk. The scoring may be effected in a variety of ways, as by marking the cards with a suitable graphite pencil to make an electrical conducting mark, or by using a conducting ink such as a quick drying aquadag solution. The use of a pencil has been found most practical because of the ease with which corrections can be made by erasures.

The scanning apparatus comprises a pair of contact brushes for each line of each of the notation cards, these contacts being in the grid circuits of vacuum tubes having relays in their output circuits. The relays operate to connect the selected tone generators to the output system and to determine the tone quality, tone intensity envelopes and the like. One of the rows of markings on the record cards may be utilized to control the operation of the instrumentation sequence scanner, this preferably being weight or spring operated and released to move a single step through a suitable electromagnetically operated escapement mechanism. Thus whenever a major change of instrumentation is desired a mark will be placed upon the notation cards to cause advancing of the instrumentation sequence scanner one step. The latter scanner is similar to that of the notation scanner but the relays operated under its control effect more or less overall changes in instrumentation and vibrato and the like.

Accent and overall output volume may be controlled from the notation cards. The output is supplied to a monitoring speaker and to a phonographic or similar recorder for the production of a master record from which the usual commercial pressings or other reproductions may be made. 35

Layout of apparatus

The overall layout of the apparatus may best be understood by the reference to Fig. 1 in which the arrangement is diagrammatically illustrated. The time sequence table 30 bears the notation cards which control the operation of the time sequence scanner 32. This scanner operates through relays and solenoids to control the operation of the instrumentation sequence table 34, with its scanner 36, as well as to control the operation of direct current control systems I, II, III and IV illustrated as blocks 41, 42, 43 and 44.

Furthermore, relays controlled by the scanner 32 control accent systems I to IV illustrated in Fig. 1 as blocks 51, 52, 53 and 54 respectively. In addition, the scanner 32 controls the operation of an overall expression control 56.

The instrumentation sequence scanner controls the vibrato introducing means 61, 62, 63 and 64 respectively for the tone generating systems I to IV shown as blocks 71 to 74. In addition, an instrumentation frequency scanner 36 controls the operation of tone quality systems I to IV shown as blocks 81 to 84 and volume systems I to IV shown as blocks 91 to 94 respectively in Fig. 1. Each of the tone generating systems 71 to 74 supplies musical tone signals to the direct current control systems 41 to 44, respectively, and the signals from the latter are supplied to the tone quality systems 81 to 84 respectively. As modified by the tone quality systems, the signal is supplied to the accent systems 51 to 54, and the output thereof is amplitude controlled by the volume systems 91 to 94. The outputs of the latter volume systems are supplied to the expression control apparatus 56 and the signal from the latter apparatus

is supplied through an output system 95 to a recorder 96 or monitoring speaker 97, or both, depending upon the positions of manually operated switches 98 and 99.

Scanning apparatus

The notation cards which are placed upon the time sequence table 30 as well as the instrumentation determining cards mounted on the instrumentation sequence table 34 are preferably of the general form indicated in Fig. 14. The card 100 shown in Fig. 14 is provided with a locating aperture 101 and an alignment aperture 102 to maintain it in proper position on the time sequence or instrumentation sequence table. The details of the markings appearing on the cards 100 of Fig. 14 will be described hereinafter but it will be noted that the card is provided with a plurality of markings such as 104, these markings being of graphite, aquadag or similar conducting material which may be readily applied to the cards.

The scanning apparatus shown in Fig. 2 comprises a pair of contact brushes 106, which may be in the form of thin wires of Phosphor bronze or similar resilient conducting material, and are arranged to brush along the surfaces of the cards 100 as the scanning apparatus moves along the time sequence table (or as the instrumentation sequence table moves past its scanner). Upon passing a conducting mark 104 on a card associated with a pair of the contact brushes 106, a circuit from the positive terminal of a source of plate current 108 to the control grid 110 of a pentode 112 is completed, this circuit including a suitable series grid resistor R114. When the contacts 106 are not in engagement with a conducting mark, the pentode 112 is negatively biased substantially to or beyond cutoff by connection of the grid 110 to the negative terminal of a bias battery 116, the connection to the grid 110 being through the resistor R114 and a resistor R115, the latter having a capacitor C117 in shunt therewith. The cathode and suppressor grid of the pentode 112 are illustrated as connected to ground, this being the potential of the negative terminal of the voltage source 108 and the positive terminal of the biasing voltage source 116. The screen grid of this pentode is connected to the positive terminal of the plate voltage source 108.

A direct current control circuit impedance illustrated as a resistance R_{118} is connected between the plate of the pentode 112 and the positive terminal of the source 108, while a control means 41—44, which may or may not include a relay (as will appear from the description of Figs. 6 and 3), is connected across the plate load resistor R_{110} of the pentode 112. This means controls the transmission of tone signals from a tone generating system 71 to 74 to a transmission means 120, which may be considered as comprising elements contained in blocks 81—84, 51—54, 91—94, 56; 95, 96 and 97.

It will be apparent from a consideration of the circuit shown in Fig. 2 that when contact between brushes 106 is completed by engagement of a conducting mark 104 on one of the record notation cards 103, the grid 110 will rapidly shift positive with respect to the cathode of the pentode 112 causing a sudden flow of plate current. The resulting drop in voltage across the impedance $R113$ provides a substantial signal impulse through the conductor 119 which connects the plate of pentode 112 with the control means.

41-44. As a result, the wires 119 may be long and those for the various pentodes 112 (of which there are in the illustrated embodiment 168 in the time sequence scanner and 112 in the instrumentation frequency scanner) may be joined in a cable without danger of interference by inductive or capacitative coupling between the individual wires or of resistive leakage. The plate current drawn by the tube 112 is relatively constant and independent of the actual impedance at the pencil marks, being, in all cases, limited by the series grid resistor R114 to that value that just corresponds to the initial flow of grid current.

In some instances it may be desirable to couple the contact brushes 106 directly to the control means, as illustrated in Fig. 3. In this figure the signal from a source such as 71-74 is impressed directly across the input circuit of a non-linear control pentode 122, the character of the input signal being capable of being modified to some extent by closing a switch 124 to connect a capacitor C125 in parallel with a capacitor C126 and with a grid resistor R128. The contact brushes 106 control the potential of the cathode from a value beyond cutoff to a suitable operating potential by connecting the cathode to a suitable negative potential source, shown as a terminal -135 v., through an appropriate tonal envelope attack and decay network comprising capacitors C130 and C131 and resistors R132 and R133. Suitable operating potentials are applied to the remaining electrodes of the pentode 122, the plate potential being applied through load resistor R134. The signal appearing across the load resistor R134 is impressed upon the transmission means 120.

In operation, completion of a circuit across the contact brushes 106 results in increasing the cathode to screen potential on the pentode 122, thereby to cause plate current flow at a rate determined by the mesh C130, C131, R132, R133, and upon breaking the circuit between the brushes 106 the cathode potential will increase at a rate, determined principally by the values of C130 and R133, to a value where screen and plate current cease to flow. C131 will ordinarily be small relative to C130 and is provided mainly to prevent undesirably rapid transients. Thus the signal originated in the generator 71-74 will appear in the transmission means 120 with an intensity envelope determined by the mesh R132, R133, C130 and C131. R132 is of value in the order of 2 megohms, thus making the resistance of the pencil mark small in comparison. The cathode voltage (as well as signal amplitude) is substantially independent of the resistance of the pencil mark. The pentode 122 will act as a non-linear class C amplifier so that only the most positive portions of the signal wave impressed upon the grid will produce a signal in plate circuit. The result will be that the output signal appearing in the transmission means 120 will vary somewhat in tone quality with amplitude, as is more fully described in the patent to Laurens Hammond, No. 2,126,464.

A further modified form of scanning means is shown in Fig. 4. In this embodiment of the invention the notation card is made of conducting material such as a metal sheet or a composite metal foil and paper sheet 143. The sheet is connected at all times to the negative terminal of the biasing battery 116. To make notations upon the conducting card 143, short strips 142 of ad-

hesive cellulose tape, or the like, are placed upon the sheet 143 at such points at which it is desired to have a tone signal controlling relay operate. The control grid 144 of a pentode 146 is connected to a single brush 148 through grid resistor R150. Thus the grid 144 is normally maintained at the negative biasing potential. Whenever the brush contacts one of the insulating strips 142, this circuit to the negative bias potential is broken and a positive potential is impressed upon the grid 144 through a resistor R152 which in this circuit is in series with R150. R152 will normally be of sufficiently high value relative to R150 that the pentode 146 will be cut off or substantially cut off whenever the brush 148 makes contact with the conducting notation card 143. When the brush passes over an insulating strip 142 the grid swings positive and plate current flows through winding 154 of a relay 156, the switch contacts of which may form part of the direct current control system 41-44. Undesirable chattering at the relay 154, due to small insulation particles or dust on the conducting notation card, is prevented by the inclusion of a small condenser C157 connected from grid to cathode.

As a further example of the manner in which the notation cards may be marked and the markings translated into a direct current, there is shown in Fig. 5 a capacity pickup system. In this system notation cards, such as the card 100, are placed upon a conducting surface provided by a metal plate 160, the markings 104 on the card being likewise made by aquadag or graphite. One terminal of a source 162 of radio frequency is connected to the metal plate 160 while the other terminal is connected to the cathode 164 of a detector pentode 166. A single brush 168, adapted to wipe past the marks 104 and to make contact therewith, is connected to the control grid of pentode 166 through a grid resistor R170. This control grid is normally connected to a suitable negative potential source through a resistor R170 and a resistor R172 in series therewith, the cutoff potential being sufficient to maintain the pentode 166 cut off despite the presence of low amplitude RF signals picked up by the brush 168 due to stray capacity effects. The output circuit of the pentode comprises a relay winding 174 having an RF bypass capacitor C176 in parallel therewith. A switch 178, closed upon energization of the relay winding 174, may be in a direct current control circuit.

From the foregoing it will appear that the apparatus shown in Fig. 5 is adapted to close the relay switch 178 whenever the brush 168 is capacitatively coupled to the radio frequency source 162 due to its contact with one of the conducting marks 104, but that normally the pentode 166 is biased beyond cutoff, so that the relay 174 is de-energized and switch 178 open.

Escapement operating circuit for instrumentation sequence table

The circuit shown in Fig. 6 is particularly adapted for the operation of the escapement mechanism of the instrumentation sequence table, to be described hereinafter. This circuit includes a pair of brushes 186 adapted to make contact with the markings 104 on notation cards 100 in the manner described with reference to Fig. 2 and thus change the grid bias on pentode 180 from cutoff to a conducting value, thereby energizing winding 182 of a relay having a switch 184. The lower contact 185 of the switch 184

is connected to ground through a relatively large capacitor C186 and is connected to an operating potential source indicated as +300 v. through a relatively high value resistor R183. The other contact of the switch 184 is connected to one terminal of a solenoid winding 190, the other terminal of the solenoid being connected to ground.

When the brushes 185 make contact with a mark 104, the relay 182 is energized to close the switch 184. It will be apparent that the capacitor C186 is at all times connected across a suitable operating potential source through the resistor R183. Therefore, when the switch 184 closes, the capacitor C186 will discharge rapidly through the solenoid winding 190 and cause the latter to operate its plunger. This solenoid must be relatively powerful for reasons which will appear hereinafter and, if it were not for the use of the energy storing capacitor C186, the solenoid would impose an undue load upon any conventional vacuum tube power supply system. By providing this capacitor, however, the drain upon the power supply extends over an appreciable time interval and thus the amperage of the current drawn is very low, but the energy supplied over such a long period of time is instantly available for energization of this solenoid winding 190, assuring quick and powerful action of this solenoid.

If desired, the scanning of the notation cards and the instrumentation sequence cards may be accomplished by photoelectric means, as shown in Figs. 7 and 8.

In Fig. 7 the card 100a bearing contrasting light intensity markings 104 is illuminated by a neon tube 194 provided with a suitable condenser lens system 196. The neon tube is energized by an alternating current source 196 of suitable frequency, such for example as 200 to 500 c. p. s. A phototube 198, having a lens system 199 directed at the portion of the card illuminated by the neon tube 194, is connected across the input of a detector pentode 200. Either of the lens systems 196 and 199, especially the latter, preferably includes a suitable mask so that each of the phototubes 198 will respond only to markings on a particular row of the card 100a, as the latter moves past the phototube, for example, in the direction indicated by the arrow. Operating potential for the phototube 198 is supplied from a suitable source through a resistor R202 and the signal therefrom is impressed upon the control grid of a pentode 200 through a capacitor C204 and grid resistor R206. A potential sufficient to bias the pentode 200 beyond cutoff is impressed upon the grid of this pentode through R208 in series with R206. The output circuit of the pentode 200 includes a relay winding 210 in parallel with a high frequency by-pass condenser C212.

From the foregoing description of the apparatus shown in Fig. 7, it will appear that whenever the phototube 198 scans a dark mark on the notation card 100a, the intensity of the signal produced thereby will decrease sufficiently that the pentode 200 will be biased beyond cutoff, thereby interrupting the plate current and deenergizing the winding 210 of the relay, permitting its switch 214 to close. When, however, the dark mark has passed the field of view of the phototube 198, a signal corresponding to the frequency of the source 196 will be impressed across the input 200 and will result in plate current flow through the relay winding 210 to open its switch 214. It will be understood that the

switch 214 will be in a direct current control circuit and control the transmission of a signal from the tone generating system to the output system of the instrument. To assure less interference from outside light sources, the portion of the notation card 100a being scanned is preferably shielded by a light shield 216.

Instead of utilizing the photoelectric scanning system to operate relays in the direct current control means, the signal produced by the phototubes in scanning markings may be used directly to control the transmission of the signal from the tone generating system to the output system, as shown in Fig. 8. In this figure the means for illumination of the card and the photoelectric pickup is substantially identical with that described with reference to Fig. 7, but the card 220 preferably is of non-reflecting black and has white notation markings thereon. The signal from the phototube 198 of Fig. 8 is impressed upon the grid of a pentode 222 through a blocking condenser C224. Suitable cutoff and light threshold bias is impressed upon the grid of the pentode 222 through a resistor R226. Thus as the amplitude of the output of the phototube 198 increases, the alternating component of the plate current of pentode 222 will correspondingly increase in value. The output of the pentode 222 is coupled through a capacitor C228 with a mesh comprising a rectifier diode 230 in parallel with a capacitor C232 and resistor R234. This mesh is connected to the cathode 236 of a non-linear signal control pentode 238 through a resistor R240. The musical tone signal generated by a source 242 is impressed across the input of the pentode 238, one terminal of the generator being connected to the grid 244 of the pentode through a decoupling resistor R246. An audio frequency by-pass capacitor C248 is connected in the cathode circuit while the remaining electrodes of this pentode are connected in the usual manner to suitable sources of operating potential. It will be seen that the output of the pentode 222 is rectified and filtered and impressed upon the cathode 236, to cause the pentode 238 to conduct plate current under the control of the signal impulses provided by the generator 242. The rate at which the cathode 236 is driven negative by the alternating signal produced in the output of pentode 222 is controlled by the values of the filtering and delaying capacitor C232 and resistor R234, and to some extent by the values of R240 and C248. By selecting these resistors and capacitors of appropriate values, the amplitude of the signal output of the pentode 238 may be made to occur with any desired predetermined tone intensity envelope upon the scanning of a notation mark on the card 220.

Notation and instrumentation sequence cards

The notation and sequence instrumentation cards are identically printed as illustrated in Fig. 14. As previously stated, the cards are approximately 11" x 12" and have imprinted thereon 56 columns numbered 301 to 366 in Fig. 14. Each column is arranged to be scanned by a pair of brushes 106 (Fig. 2). There are three rows of notation cards placed side by side and two instrumentation cards placed side by side.

The cards are preferably made of a dull finish material which will readily take pencil marks and are of several ply thickness so they may be durable and easily handled. The paper may be specially treated to render it less subject to shrinkage due to changes in humidity, and is

preferably tested to make sure that no parts thereof are electrically conductive.

In Fig. 14 the card is illustrated as having exemplary markings 104 thereon, the markings being indicated by cross-hatching. It will be noted that the columns 301 to 366 are arranged in rough simulation of a piano keyboard in that the C# and D# columns are "X'd" while the F#, G# and A# columns have parallel line shading. This facilitates marking all the cards by the arranger or composer. In order to avoid the necessity that the composer or arranger completely fill in the block markings 104, he may merely draw a line parallel to and within the column and an assistant may thereafter fill in a complete marking represented by the cross-hatching in Fig. 14.

As illustrative of the character and scope of the instrumentation available, the character of the operations controlled by the various columns of the notation and instrumentation cards which have been found practical, will be set forth.

Of the first notation card, columns 301 to 341 will be used to determine which of the notes C2 (130.81 c. p. s.) to E5 (1318.51 c. p. s.) of generating system I are to be sounded. Columns 342 to 353 of the first card will be used to determine which of the notes F0 (43.654 c. p. s.) to E1 (82.407 c. p. s.) of the bass generating system II shall be sounded. Column 354 will be marked when any note of generating system I is required to be weakly accented. Columns 355 and 356 will be marked to cause strong accents on tones of generating system I, and medium accents on the tones produced by the generating system II, respectively.

Of the second notation card, columns 301 to 341 will be marked to determine which of the notes C2 (130.81 c. p. s.) to E5 (1318.51 c. p. s.) of the generator system III shall be sounded. Columns 342 and 343 will respectively cause weak and strong accents of the tones of generator system III. Columns 344 to 356 will respectively control notes G2 (196.0 c. p. s.) to G3 (392.0 c. p. s.) of the accompaniment generator IV.

Columns 301 to 341 of the third notation card will be used respectively to control notes C2 (130.81 c. p. s.) to E5 (1318.51 c. p. s.) of a generating system V. Column 342 is used to control medium accents on the notes of accompaniment generator IV, while columns 343 and 344 are utilized respectively to control weak and strong accents on generating systems V. Columns 345 and 346 of the third card are used respectively to cause rapid and slow deceleration of the motor driving carriage to produce decelerando effects. Similarly, columns 347 and 348 are used to produce slow and rapid accelerando effects. Marks in columns 349 to 351 are utilized to produce various degrees of decrescendo effects, while marks in columns 352 and 354 are utilized to provide various degrees of crescendo effects. Marks in column 355 produce drum effects. A mark in column 356 will produce an orchestration shift, that is, a change in the instrumentation sequence table so as to effect any desired change in the overall instrumentation employed.

The first instrumentation card utilizes a mark in columns 301 to 304 to control the output volume of generating system I. Columns 305 to 308 are used to determine the register of generating system I. Columns 309 to 313 are utilized to select the tone quality of generating system I. Column 314 is used to mute the tones of generating system I, while column 315 is used to

determine whether the tones of generating system I shall have vibrato. Columns 317 to 325 control the percussion branch of generating system I, columns 317 to 320 determining the degree of volume, while columns 321 to 325 select any one of five tone qualities for the percussion branch of generating system I.

Columns 328 to 331 are used to select any one of four degrees of volume for bass generating system II, columns 332 to 334 selecting any one of three registers for this generating system, and columns 335 to 339 selecting the tone quality of the bass generating system I. Columns 342 to 354 control the operation of generating system III, the first four columns determining the volume, the next three the register, the next five the tone quality and column 354 controlling the vibrato.

On the second instrumentation card, marks in columns 301 to 310 control the output of the accompaniment generator IV, the first four columns controlling four different degrees of volume, the next five columns five different tone qualities, and the tenth column the vibrato. Columns 313 to 323 are for the control of generating system V, the first four columns of this group controlling different degrees of volume, the next five different tone qualities, while the last two respectively control the mute and the vibrato. Marks in columns 325 to 333 control the output of the percussion branch of generating system V, the first four controlling different degrees of volume, while the remainder control different tone qualities. Columns 336 to 346 control the drum section, the first four columns determining different degrees of volume, the next five different tone qualities, and the last two determining different tone intensity envelopes.

In the center of each card there are numbers 0 to 9 imprinted in alignment with transverse lines 360. The distance between these lines will normally represent the time interval of a quarter note, thus four times this distance between the lines 360 will represent a measure in 4/4 time. Intermediate the lines 360 there are dash lines 362 dividing the quarter tone interval into eighth tone intervals. There are also light lines 364 dividing each quarter tone interval into three equal parts for the scoring of triplets.

The notation card table

As shown in Figs. 9, 10 and 11, the notation card table is built up in sections, the first section 366 being constructed in the manner of a conventional table with four legs 367. The remaining table sections 368 are provided with only two legs, both at one end of the table section, the other end of the table resting upon brackets 370 projecting from the adjacent legs of the adjacent table. Suitable shims 372 are provided so as to make the tables 368 level with one another. A pair of tracks 374, preferably of inverted T-section, are secured to the tables by suitable brackets 376 and successive sections thereof are bolted together by suitable fish plates 378. By virtue of this arrangement, the tables may quickly and easily be assembled with the tracks smooth and level.

The locating pins for positioning the notation cards upon the tables are preferably of the construction shown in Fig. 11. From this figure it will be seen that each of the pins is mounted in the table top 377 projecting through an enlarged hole 380 formed in the top. Each pin 382 has a reduced diameter rounded end portion 384 for

engagement in the perforations of the cards, and has a washer 386 welded thereto. The lower end of the pin is threaded for a clamping nut 388 which bears against a washer 389, a suitable lock washer 390 being utilized. The washers 386 and 389 are of sufficiently great diameter that upon loosening the nut 388, the pin 382 may be moved in any direction within the limits of the hole 380, thereby facilitating accurate location of the ends 384 of the pins. The holes 380 may be drilled in the table with the tolerances customary in woodworking practice and after the rails 374 have been secured to the tables and all of the tables are assembled, the ends 384 of the pins may be accurately located with reference to the pins in adjacent tables so that their spacing may be accurate to a high degree of precision.

The scanning carriage

The scanning carriage, designated generally by the reference character 392, is mounted upon V-grooved or flanged wheels 393 resting on the tracks 374 and is driven by a motor 394 through a suitable speed reducing gearing which is enclosed in the motor housing. Suitably mounted on the carriage are 168 pairs of brushes 106 which project downwardly at an angle so as to resiliently contact the three cards placed side by side upon the surface of the table. Most of the elements of the circuit shown in Fig. 2, such as the pentodes 112 and circuit elements R114, R115 and R118 and C117, are also carried by the carriage. The conductors 119 from the fifty-six pentodes 112, as well as conductors supplying operating potential for these pentodes are bound in a flexible cable 396 leading to the other components of the apparatus.

The instrumentation sequence table

The instrumentation sequence table is shown in Figs. 12 and 13 as comprising a base 400 having a pair of V-grooved rails 402 mounted thereon for the reception of ball bearings 404. A movable table 406 has corresponding grooved rails 408 which rest upon the balls 404, thus providing an anti-friction support for longitudinal movement of the table 406 relative to the base 400. Suitable locating and aligning pins 382, 384 are provided for properly positioning a pair of cards 100 (Fig. 14) upon the table 406.

Along the center of the table are two rows of staggered upwardly projecting pins 410 for cooperation with an escapement pawl 412 which is suitably pivoted on a cross frame 414 and operated by a solenoid 190. The table 406 is drawn rearwardly by a long tension spring 418 which has its end respectively anchored to the base 400 and a pin 420 projecting downwardly from the table 406. The cross frame 414 is guided for vertical movement in a pair of grooved posts 422 projecting upwardly from the base 400. The cross frame carries two banks of contact brushes 106, there being 56 pairs of contact brushes 106 in each bank. These contact brushes cooperate with the markings on the cards 100 to complete circuits and cause energization of relays in a manner such as disclosed in Figs. 2, 4 or 5.

Thus when there is a conducting mark in column 356 of the third notation card, the contact brushes 106 making contact therewith will render the tube 180 (Fig. 6) conducting, energizing the plate circuit relay 182, 184 and permitting the charge stored in the capacitor C186 to energize the solenoid 190. Whenever the solenoid 190

is energized, the escapement pawl 412 is shifted back and forth so as to permit the spring 418 to draw the table 406 one step toward the rear (upward of Fig. 12) thereby to bring the next set of instrumentation controlling marks into engagement with the banks of contact brushes 106. The completion of the circuits, such as those in Figs. 2, 4 or 5, associated with such of these brushes as contact marks on the card, results in energization of relays which, as indicated in Fig. 1, cause changes in the character of the output signals of the various generating systems.

The system as a whole is preferably rendered more flexible in use by providing means whereby the connections of the conductors 119 (Fig. 2) may be selectively coupled to any of the various control means. In this way there may be as many tone generating systems as desired and only those selected for the rendition of a particular composition may be coupled to the instrumentation sequence scanner.

Expression control and volume system

The expression control indicated by the block 56 in Fig. 1 and the volume control systems represented by the blocks 91 to 94 of Fig. 1 are preferably of the nature shown in Fig. 15.

In the latter figure the output systems of seven generators are diagrammatically illustrated, these 30 output systems corresponding to the outputs of the tone quality systems 81 to 84 of Fig. 1, each being illustrated as being coupled by a transformer having a secondary winding 430 to the input of a preamplifier triode 432 through meshes 35 comprising resistors R433 to R438 in series and shunt resistors R439 and R440. Each of the resistances R433 to R437 is shunted by a switch 441 operated by a relay 441a, these relays being operated by the scanning brushes 106 when they 40 contact appropriate markings on the notation cards of the time sequence scanning system.

The resistors R433 and R434 are of properly graded values so that upon energization of the 45 relays associated with resistors R433 and R434 different degrees of accent will be produced by changing the impedance of the mesh, which includes these resistors, for the particular generating system upon which the accented note is desired. Likewise the resistors R435, R436 and 50 R437 are preferably of such values that upon successive operation of the relays 441a associated therewith the volume may be increased and decreased logarithmically. The shunt resistors R440 of the various outputs of the generating 55 systems are connected in series between ground and the decoupling resistor R430 so as to mix the signals of the various generating systems.

The amplitude of the combined signal of all the 60 generating systems has its amplitude controlled by decrescendo relays 441b, 442 and 443 and crescendo relays 444, 445 and 446. The relays 441 to 443 upon energization are adapted to connect the control grid of the preamplifier triode 432 to a grounded conductor 437 respectively through resistors R443, R449 and R450. These resistors are of graded values so that upon successively energizing the relays 443, 442 and 441b the amplitude of the combined signal appearing on the grid 432 will be decreased in logarithmic 65 steps. On the other hand, the energization of the relays 444, 445 and 446 will result in opening circuits through resistors R451, R452 and R453 so as successively and in a logarithmic manner increase the effective resistance between the 70 grid of triode 432 and the grounded conductor 75

447. In this manner overall crescendo and decrescendo effects may readily be obtained by appropriate markings in the six columns of the notation card.

The output of the preamplifier triode 432 is coupled to a power amplifier 454 (forming part of the output system 95—Fig. 1) and supplied to the monitoring speaker 97, or the recorder 96, or both.

Octave coupler system

As shown in Fig. 16, suitable controls are preferably provided in the apparatus for effecting octave coupling so that by the provision of a single mark upon the notation card the output signals of a number of octavely related generators of a particular system may be simultaneously coupled to the output of the apparatus as a whole. In Fig. 16 there are five pairs of scanning contact brushes 106 which are representative of the brushes cooperable with two or three octaves of markings for a particular generating system. Each pair of brushes operates through a pentode such as 112 (Fig. 1) to control a relay, these relays bearing the reference characters 460, 461, 462, 463 and 464 respectively. These relays, upon energization, are adapted to connect a source of suitable operating potential, indicated as +210 v., to bus conductors 470, 471, 472, 473 and 474 respectively. A plurality of octave coupler control relays 475, 476, 477 and 478 (Fig. 16) are adapted to be energized by appropriate markings upon the instrumentation sequence cards, and respectively control the addition of the second octave, the octave, the unison, and the sub-octave. Each of the relays 475 to 478 has a plurality of switches 479, one associated with each of the bus conductors 470 to 474, so as to connect the latter through a high value decoupling resistor R480 to the input of one of the plurality of suitably biased rectifier pentodes 482. Connections between the resistors R480 and the rectifier tubes 482 are such that when the relay 477 is energized and a relay such as 468 is energized, only the note represented by the marking which has resulted by the energization of relay 468 will be sounded, whereas if in addition the relay 476 is energized, the note and its octave will be sounded, since in this case the bus 470 will be connected through two decoupling resistors R480 to different rectifier pentodes 482 as will hereinafter appear. This will result in sounding of the note and its octave.

Each of the rectifier pentodes 482 has a relay 484 in its output circuit, this relay being adapted upon energization to connect a suitable potential shown as -135 v. to the cathode of a control pentode 486 through a circuit identical with that shown in Fig. 3 and operating in the same manner to cause the transmission of a signal from a tone generator 71—74 to its output system represented by a signal collector conductor 488.

Since in Fig. 16 only a representative portion of a complete octave coupler system is disclosed, the generators 71—74 will generate octavely related frequencies such as those of the notes C1 to C6, while the relays 460 to 464 will be respectively associated with the contact brushes 106 of the card columns representing octavely related notes C2 to C3.

The resistors R480 are of high value relative to the input impedances of the pentodes 42. Thus when two or more of the relays 475 to 478 are energized at the same time, no spurious circuits can be completed because the resistors R480, being of high value (with respect to the grid-to-cathode

resistance when the grid is drawing current) prevent substantial current flow in a reverse direction. For example, if the relays 477 and 478 were energized and the note controlling relay 460 energized the first and second pentodes 482 (from the top) would have an operating potential impressed upon their grids, sufficient to cause grid current flow and thus to reduce their input resistances from infinity to a value low in comparison with R480.

10 Thus, this enormous drop in input impedance prohibits a substantial current to flow from the grid conductor of the second pentode 482 through its associated resistor R480 to the conductor 471. It will be apparent that if there were any appreciable flow through said last named resistor R480 to the conductor 471, current might also flow to the grid of the third pentode and energize the latter. However, as each of the pentodes 482 is rendered conducting and at 15 very low input impedance by impressing the high grid voltage (+210 v.) on its grid circuit through R480, there is sufficient grid-to-cathode current flow in the pentode so that the actual potential of the grid is very low and, therefore, there cannot be a sufficient potential buildup upon grids of other pentodes 42 through the previously described spurious paths to cause the latter to conduct current.

In Fig. 16 it is assumed that the generator system is of limited gamut, extending through the note C6 but not extending to the note C7. As a compromise result, the switches connected to bus conductor 474 and associated with the relays 475, 476 and 477 and the resistors R480 connected thereto are in parallel and connected to control the generator for the note C6.

The generating system employed with the octave coupler control system of Fig. 16 is preferably of the type shown in the patents to L. 40 Hammond Nos. 2,126,464 and 2,126,682. It will be noted that the method of signal amplitude control which includes the pentode 486 of Fig. 16 is similar in principle to that disclosed in said Patent No. 2,126,464.

45 *Xylophone tone signal generating system*
It is nearly a practical necessity for the artistic rendition of orchestral music that percussive tones be employed to provide contrast to the sustained tones and, therefore, means for producing percussive tones of the xylophone type, as shown in Fig. 17, is provided. In Fig. 17 contact brushes 106 are adapted, through the pentode 112, to control the operation of a relay 490, which upon energization connects a negative potential source, indicated as -135 v., through a mesh, comprising resistors R491, R492, R493 and R494, to a terminal 495 of the tone quality system 84. The resistor R492 has a capacitor C496 in parallel 50 therewith and the junction between the resistors R493 and R494 is connected to ground through a resonant mesh comprising an inductance L497 and a capacitor C498. A control pentode 499, which corresponds to one of the pentodes 486 (Fig. 16) is adapted to control the output of a suitable signal generator 71—74, the output of the pentode 499 being suitably coupled to a tone quality system 81—84. The terminal 495 represents a common terminal for a plurality of the meshes R491 to R494, C496, C498 and L497 associated with other relays similar to relay 490.

70 The frequency generated by the particular tone generator 71—74 associated with the pentode 499 is preferably the same as that at which the mesh 75 L497, C498 is resonant. Upon energization of

the relay 490 the transient produced upon closure of its switch is transmitted to the terminal 495 through the intervening mesh, but only such frequencies as correspond rather closely to frequencies of the generator 71-74 will be transmitted to the output system. The resonant mesh L497, C498 does not have a sufficiently high Q to exclude frequencies differing by as much as a semitone or more from the output and therefore this signal is heard as a percussive musical tone of recognizable but not as clearly defined in pitch as the usual sustained type of tone.

Upon closure of the switch of relay 490 the negative 135 v. potential is impressed upon the cathode of the pentode 499, through the resistor R491 and additional attack resistor R500, at a rate determined in part by capacitor C501, thereby rendering the pentode 499 conductive of the signal supplied by the generator 71-74. After deenergization of the relay 490, cathode current is still supplied to the pentode 499 from the capacitor C501, so that the tone will decay at a gradual rate determined by the relative values of R500 and C501. Thus upon energization of the relay 490 a signal constituting both a percussive tone and a sustained tone (the latter being produced by the generator 71-74) of rapid attack and slightly slower decay, will be produced in the output system. This tone will be respectively of the xylophone and brass types and will be useful in many orchestral renditions.

Generator system for percussive piano-like tones

In Fig. 18 there is illustrated a circuit suitable for the control of the tone envelope of a generator system producing sustained tones, under the control of conducting markings on a notation card. In this circuit contact brushes 106, upon passing over a conducting mark on the card, change the grid bias of a pentode 502 from a negative value beyond cutoff to a positive value in a manner similar to that previously described with reference to Fig. 3. In Fig. 18, however, the pentode 502 operates as an impedance changer so that the value of the resistance imposed by the marking on the card across the brushes 106 is not of controlling character. This is because the pentode 502 decouples the card mark and cable impedances from the remainder of the circuit which is of high impedance and would be susceptible to spurious leakage, etc. The anode of the pentode 502 is supplied from a suitable source of plate voltage through a resistor R504 in parallel with a capacitor C506. The anode of the pentode 202 is also connected to the cathode 508 of a control pentode 510 through a resistance R512. The pentode 510 has a sharp peak wave impressed thereon by a generator 71-74 and the output of the pentode is suitably coupled to a signal collector conductor 514 through a capacitor C516 and a decoupling resistor R518. The anodes of a plurality of pentodes 510 may be connected to the collector conductor 514 through the same capacitor C516 and resistor R518.

When the contact brushes 106 pass over a control marking on a notation card, the pentode 502 is rendered conducting so that the potential of its plate drops at a rate determined by the tube characteristics and the values of C506 and R504. This drop in plate potential is reflected on the cathode 508 of the pentode 510 and therefore renders the latter conductive of the signal impressed upon its input circuit. It will be noted that the plate of pentode 502 is normally at a

potential of 7 volts above that of the cathode 508 due to the provision of a battery 516. This latter potential normally completely cuts off plate current in tube 510.

The circuit of Fig. 18 is of advantage over some of the previously described control circuits in that no electromagnetic relay is required.

Apparatus for producing drum signals

10 An important element of orchestral music, particularly that of popular nature, is imparted by the percussion beat of drums. I have therefore provided a means for electronically producing electrical signals corresponding to the beats of drums. Such an apparatus is shown in Fig. 19 as comprising the random frequency generator 520. This generator may be any suitable source of random noise such, for example, a signal picked up from the phonograph record of the noise of 15 waves breaking on a beach, but is preferably an electronic generator utilizing the noise due to thermal agitation as the signal source. A generator of this type is disclosed in the copending application of applicant and David Hancock, Serial No. 447,770, filed June 20, 1942, which has matured into Patent Number 2,432,152, dated December 9, 1947.

The output of the random frequency generator 520 is connected to the primary of a transformer 30 T522 by a high-frequency attenuating mesh comprising resistors R524, R525 in series and a shunt mesh comprising R526 and C527. A load resistor R528 is connected in parallel with the primary winding of a transformer 522. The secondary of the transformer 522 has a center tap connected to a suitable biasing potential source indicated as a terminal -7 v. and has its terminals connected to the grids of a pair of push-pull pentodes 530, 531. The screens of the pentodes 10 530 and 531 are connected to the cathodes thereof through a time constant capacitor C532 and resistor R534. Plate potential is provided from a source indicated as a +300 v. terminal through load resistors R536 and R537 as well as 15 through the center tap primary of an output transformer T538. The screen grids of the pentodes 530 and 531 are normally maintained at ground or cathode potential by virtue of their connection to the cathodes of these tubes by the 20 resistor R534. When the contact brushes 106 for the control of this percussion generating system pass over a mark on the notation card a relay 540 is energized to connect the screen grids of the pentodes 530, 531 to a suitable source of operating potential shown as a +100 v. terminal, this connection being effected through an attack resistor R542. Two or more capacitors C543, C544 are adapted to connect the screen grids to ground upon closure of switches 545, 546 respectively. When both switches 545 and 546 are open, the screen grids of the pentodes 530, 531 will be rapidly raised to operating potential when the relay 540 is energized, and thus produce a percussion tone with a very sharp attack. When it 25 is desired to lessen the sharpness of this attack and to prolong the decay period of the percussion drum tone, either switch 545, or switch 546, or both, will be closed, thereby slowing up the rate at which the substantially 100 volt potential may 30 be built up on the screen grids and prolonging the period during which an operating potential will remain on the screen grids and thus prolonging a period of decay of the tone. The secondary of the output transformer T538 is suitably coupled to one of tone quality systems 81 to 84, and

may be coupled through an intermediate amplifier 548 with the accent and volume systems 51, 54, 91-94 to the expression and output system which may include the elements 56, 95, 96 and 97 of Fig. 1.

Since the mesh coupling the random frequency generator 520 to the transformer 522 is not particularly frequency responsive, a wide range of audio frequencies will be present in the output system whenever the relay 540 is energized and such wide band of audio frequencies will produce a drum-like sound, the rates of attack and decay of which may be controlled by appropriate operation of the switches 545, 546. These latter switches may be operated manually or by means of relays controlled by marks on the instrumentation sequence cards.

Quality control circuits

Fig. 20 illustrates a representative portion of suitable circuits by which the outputs of the generators of a signal generating system for signals having high harmonic development may be quality controlled. Thus in Fig. 20 there are shown groups of plates 550 (which might be, for example, the plates of the pentodes 510 of the system shown in Fig. 18), these plates being coupled to a suitable plate voltage source such as 300 v. through load resistors R552 and connected to a collector conductor 554 through blocking capacitor C556 and resistors R558. The collector conductor 554 is connected to ground through a plurality of filtering elements and meshes comprising an inductance L560, meshes 561, 562 and 563, each comprising an inductance, capacitance and resistance in parallel, a resistance R564 and a mesh 565 comprising a resistance and capacitance in parallel. These elements have suitable values so as to attenuate certain frequencies when rendered effective in the circuit between collector conductor 554 and ground. A determination of which of the elements or meshes 560 to 565 is energized is accomplished by relays 570 to 575. It will be noted that the switches of these relays 571 to 575 are respectively in shunt with the impedances 560 to 564 and thus to render any of the latter impedances effective, its associated relay must be energized. The relays 570, 571 must be shielded and therefore these relays are respectively energized by relays 580 to 585 respectively, the latter relays being controlled by markings on the instrumentation sequence cards through circuits such as shown in Figs. 2, 4 and 5. The relays 570 to 575 may thus be selectively energized either singly or in any desired combination to produce any one of a variety of tone quality changes in the signal outputs of the various generators of the system. Such output signal, as modified by these quality controls is supplied to a preamplifier 548 from which the signal is supplied through accent and volume control systems 51-54, 91-94 to an expression output system corresponding to the components 56, 95, 96 and 97 of Fig. 1.

Accelerando and decelerando

In the rendition of certain compositions it is desirable at times to accelerate or decelerate the tempo and this is accomplished in the present invention by changing the speed of the motor 394 (Fig. 21) which drives the carriage 392 used to scan the notation cards. The control for such speed changing of this motor is effected by appropriate markings on the notation cards, this

scanning of these marks resulting in energization of relays 586 or 587 or both of these relays to effect accelerando, and the energization of relay 588 or 589 or both of these relays to produce different degrees of decelerando. The carriage driving motor 394 is illustrated as being of a series type supplied with 115 v. direct current potential through one or more of resistors R590, R591, R592 and R593. Resistors R590 and R591 are of different values and the resistors R592 and R593 are likewise of different values. Resistors R590 and R591 are normally in series with the field and armature of the motor 394 but upon energization of their associated relays 586 and 587 are respectively shunted. Resistors R592 and R593 are normally shunted by switch of relays 498 and 599, but upon energization of the latter relays, are effectively in series with the motor 394. Thus to produce a certain increase in tempo R590 is cut out of the motor circuit by energization of its relay 596. To produce a greater increase of speed R591 is cut out of the motor circuit by energization of its relay 587. To produce the maximum degree of increase of the speed of the motor, both R590 and R591 are shunted out of the circuit by energization of their associated relays.

In a similar manner energization of relay 588 renders R592 effective in the motor circuit to decrease the voltage impressed thereon and reduce its speed to a certain extent. Energization of R589 and consequent insertion of R593 in the series motor circuit causes a greater decrease in motor speed whereas deenergization of both relays 588 and 589 results in reducing the speed of this motor to its minimum.

It will thus be seen that by making appropriate markings on the notation cards in the accelerando and decelerando columns, the speed at which the composition is rendered by the instrument may be increased and decreased to produce different degrees of accelerando and decelerando effects.

Modified form of marking and sensing means

In Fig. 22 there is illustrated a modified means for sensing markings on the card, by which the operation of marking the notation cards may be simplified. In this method of marking, the card 100, instead of having black markings of length corresponding to the duration of the tone to be produced, has two marks, one representing the beginning of the sounding of the tone and the other representing the termination of the tone. Thus, for example, in Fig. 22, the line 600 marked with a conducting pencil or conducting ink upon the card is to cause the starting of a tone whereas the mark 601 is to control the termination of the sounding of the tone. These markings are adapted to be contacted by brushes 602, which are similar to the brushes 106 but preferably have a greater portion of the ends thereof resting in contact with the card so that the circuit between the brushes will be completed by a line which is not exactly perpendicular to the direction of relative movement of the brushes and card.

One of the brushes 602 is connected to a suitable source of potential indicated as a +300 v. terminal, while the other brush is connected to the grids of alternate pulse responsive triggering triodes 604, 605 through a multi-section filtering mesh comprising series resistor R606, series capacitors C609, C610 and C611 and shunt resistors R612, R613 and R614, each having a capacitor C616, C617 and C618 in parallel therewith. The

grids of triodes 604, 605 are connected to a negative biasing potential source, indicated as a terminal -50 v., through resistors R620 and R621 respectively, while the cathodes thereof are connected to ground. The plates of these triodes are connected to a suitable source of potential, indicated as a terminal +300 v., through resistors R622 and R623, the latter resistance having the winding of a relay 624 in parallel therewith. The plate of triode 604 is connected to the grid of triode 605 and the plate of the latter is connected to the grid of the former respectively through resistance capacitor meshes 626 and 627.

As the brushes 602 sense a mark, such as the mark 600, a pulse will be transmitted to the grids of triodes 604, 605 but the wave shape of this pulse will be determined by the multi-section filtering mesh between the brushes 602 and the inputs of triodes 604, 605. The triodes 604, 605 are alternately conducting. When for example the triode 604 is conducting, the plate voltage of this tube drops and this drop in voltage is reflected through the mesh 626 to the grid of triode 605. If, however, when the pentode 604 is conducting, a positive pulse is impressed upon the grids of both of these triodes, due to a pencil mark contact having been made between the brushes 602, the pentode 605 will commence conducting current and, as a result of the drop in its plate voltage reflected upon the grid of triode 604 through the mesh 627, the latter triode will be substantially cut off. The circuits for the triode 604 or 605 are mutually exclusive so that only one of these triodes can be conducting full plate current at any one time.

Thus when the brushes 602 scan the mark 600, assuming the triode 604 is conducting current, a pulse resulting in the completion of the circuit through the brushes 602 will cause the triode 605 to be conducting and the triode 604 to be substantially cut off. Rendering the triode 605 conductive results in energization of the relay 624. The circuit completed by this relay will be arranged to cause the coupling of a predetermined tone signal generator to the output system of the instrument, or may be used to complete any other desired control circuit.

Relay 624 will remain energized until a circuit is again completed through the brushes 602, as when the mark 601 is contacted by these brushes. The pulse thus produced will be impressed upon grids of both triodes 604 and 605 and result in rendering the triode 604 conducting and substantially stopping plate current flow through triode 605. As a result, the relay 624 will be deenergized to interrupt the circuit between the selected tone generator and the output system. By virtue of this circuit arrangement the first of two marks on the notation card 103 contacted by the brushes 602 will cause energization of the relay 624, while contact with the second mark will cause deenergization of this relay. The composer or arranger need not therefore spend the time and effort to fill in the space between the two marks with a conducting mark which, of course, makes it possible more quickly and easily to mark the notation cards and also makes it easier to make changes in the marking to correct for errors in marking or to improve the musical rendition. Of course, it is essential that the type of scanning circuit shown in Fig. 22 with the relay 624 be deenergized at the commencement of the scanning operation. If it is not, such deenergization can be accomplished

merely by momentarily connecting the brushes 602.

Due to the provision of the filtering mesh between the brushes 602 and the grids of the triodes 604, 605 the high frequencies present in the pulse are attenuated so that the possibility of the relay 624 being operated by spurious short pulses or by unduly long pulses is eliminated, and the pulses impressed upon the grids of the triodes are made of such wave shape as to assure reliable triggering of these triodes.

Operation

The use and operation of the various components of the apparatus have been described in conjunction with the foregoing detailed description and it is therefore necessary at this time merely to give a brief resume of the manner in which the apparatus is used and operates.

- 20 A composer or arranger may at any convenient time and place mark the notation and instrumentation sequence cards with a single line extending along the column for the duration of sounding of each note desired, and an assistant 25 may later block in the marking in the manner illustrated by the cross-hatching marks 14, if the first described system of marking is used. In the system of marking described with reference to Fig. 22, he will make two horizontal marks 30 across the column, one to indicate the commencement of the sounding of the note and the other to indicate the termination thereof, the space between such markings therefore representing the duration of the tone.
- 35 In the first effective line of the instrumentation sequence cards he will suitably designate the character of the instrumentation desired for the first bar or other division of the composition, indicating on this card the various types 40 of tone quality, accents, volumes and vibrato desired. He will then proceed with the marking of the notation cards until it is desired to change the instrumentation whereupon he will place a mark in the column 356 of the rightmost notation card to cause progression of the instrumentation sequence cards one step, and then will 45 mark the latter cards to represent his desires as to the instrumentation to be employed for the next bar or section of the composition. He will proceed in this manner until all of the cards, or 50 any desired portion of them have been marked.
- Each of the cards during the course of its marking will have appropriate sequential numbering thereon to indicate its appropriate location upon the time sequence table 30 and therefore at any desired time the cards may be laid upon the time sequence table in the required order in a manner of laying shingles, (that is, overlapping). Assuming that all of the various 55 tone generating systems and controls are properly energized, the carriage motor 394 is started. After the apparatus is started, the composer or operator need do nothing further but listen to the composition as rendered by the apparatus.
- 60 Ordinarily, the composer will wish to listen to the composition many times before making a recording, and to accomplish this he would have the switch 85 closed and the switch 86 open (Fig. 1). If, during the course of rendition of the 65 composition the composer or arranger notices any tones which are improper, either due to incorrect marking on the notation cards, or to errors on the instrumentation sequence cards, he may easily erase the marks which caused the 70 improper note or instrumentation and replace 75

it with the desired marking. Also, during the course of rendition of the composition, the composer may make memoranda of the manner in which the rendition input may be improved as by varying the tempo from time to time, accenting different notes, changing the instrumentation, adding parts and making such similar changes which would, in his opinion, improve the rendition of the composition.

From the detailed description it will become clear that the composer or arranger may, merely by making appropriate markings upon the notation and instrumentation sequence cards, produce without substantial limitation, any desired orchestral type of rendition of the composition. There are no human limitations imposed as with conventional hand-played instruments.

Having marked the cards to his satisfaction, a recording, either on a master phonograph record, wire recorder, or sound on film, may be made by closing the switch 98 (Fig. 1) and such recording will duplicate in every respect the rendition previously heard.

After the recording has been made, the cards may be removed from the tables and stored as a permanent record to make an additional master record at any time this might be required.

The apparatus is of peculiar utility for providing musical accompaniment for motion picture films. In adding music to motion picture films, the film may be completely arranged in final form and then knowing the speed at which the picture is to be reproduced, it is a very simple matter for a composer or arranger to lay out upon the notation and instrumentation sequence cards a musical selection timed exactly to that of the motion picture. The output of the apparatus may then be recorded photographically either directly on the film negative or upon a separate negative which is to be combined with the picture negative, and such recording and combining may be effected without the necessity of any cutting of the sound film record and without requiring matching it to the picture film.

The above described method of providing musical accompaniment for motion pictures is particularly adaptable for animated cartoons in which all of the action is predetermined and takes place in definite time sequence. Thus the musical accompaniment may readily be made to fit exactly the action of the animated cartoon.

Most popular musical recordings require the addition of a voice recording and this may very easily be accomplished with the present apparatus by providing the customary mixer to introduce the vocal signals into the recording apparatus. In accomplishing this the singer will have the advantage that he may listen to a suitable monitoring speaker or earphones while singing and thereby accurately time his singing with the musical accompaniment.

With the apparatus disclosed it is easily possible to produce music of a tonal and dynamic character, complexity, and technical perfection unattainable by the usual manually played instruments, as in a conventional orchestra. Only the efforts of the composer or arranger are required to prepare and produce the finished electrical music and record thereof. Furthermore, the operator need not be a musician in the sense of having technical skill in playing any musical instrument.

By using this apparatus the composer or arranger functions much the same as a painter. He literally draws a picture of the musical com-

position to be performed, indicating the various notes, accents, expressions, tone color and other kindred matters in the form of written notations. With the apparatus of the invention it becomes possible to secure a "perfect performance," that is, one in which the finished musical production is exactly in accord with the composer's conceptions of the musical result desired.

It is a feature of major importance of the apparatus and method employed that any portion of the composition may be changed or rearranged with great facility, leaving the remainder of the musical composition without change.

The apparatus is also of great utility for use by composers for testing and perfecting their musical scores. Amateur composers likewise have an opportunity to hear and make a recording of an orchestral rendition of their scores. This is not ordinarily possible because of the great expense of employing an orchestra to rehearse and produce the composition. The time consumed in making the musical notations upon the time sequence and registration cards is comparable to that required for the preparation of the usual orchestral scores.

Because the apparatus employed has substantially no limitations as to the speed with which the notes may be played, arpeggios, trills and the like may be sounded with a celerity and technical accuracy impossible of attainment in the manual playing of any instrument. Thus the apparatus is capable of producing music of a character never before realizable. The imagination and skill of the composer or arranger are the only limitations upon the character of the music which may be produced. In a very practical sense the apparatus comprises a means for directly translating the mental concepts of the composer into a finished orchestral production.

While I have shown and described a particular embodiment of my invention and various components thereof, it will be apparent to those skilled in the art that numerous variations and modifications may be made without departing from the underlying principles of the invention. I therefore desire, by the following claims, to include within the scope of my invention, all such modifications and variations by which substantially the results of the invention may be obtained by substantially the same or equivalent means.

I claim:

1. In an apparatus for the rendition of musical compositions and having an output system including electrical sound signal amplifying and recording means, the combination of a record having a plurality of markings thereon, means for scanning said record, relay means individually operable by said scanning means depending upon the position of the markings thereon, a plurality of electrical tone signal generators, and means operated by said relay means for selectively rendering said generators operative to supply signals to the output system.

2. In an apparatus for the rendition of musical compositions said apparatus including an output system, the combination of a record having a plurality of electrically conductive markings thereon, means for scanning said record comprising brushes arranged to contact the markings on said record and thereby to complete electrical circuits, relay means individually operable upon completion of said electrical circuits, a plurality of tone signal generators, and means operated by said relay means for selectively render-

ing said generators operative to supply signals to the output system.

3. A record apparatus comprising an elongated table having a plurality of accurately located pins thereon, said pins being equally spaced in a direction longitudinally of the table, and a plurality of record cards each having a locating perforation and an aligning perforation, with each of the cards having its locating perforation embracing one of said pins and its aligning perforation embracing the next adjacent pin, with said cards overlapping successively so as to provide a surface over which contact brushes may slide freely in one direction.

4. A record apparatus comprising an elongated table having a plurality of accurately located upwardly projecting pins thereon, said pins being equally spaced in a direction longitudinally of the table, and a plurality of record cards each having a locating perforation and an elongated aligning perforation, with each of the cards having its locating perforation closely embracing one of said locating pins and its aligning perforation embracing the next adjacent locating pin, with said cards overlapping successively so as to provide a surface over which contact brushes may slide freely in one direction, said elongated perforations in the cards permitting expansion and contraction of cards with changes in humidity while holding the cards in accurate longitudinal alignment and uniformly spaced.

5. In an apparatus for rendering musical compositions of an orchestral nature, the combination of a table having a row of equally spaced locating pins projecting upwardly from the top surface thereof, a plurality of record cards each having a locating perforation and an aligning perforation therein, the locating perforations in the cards being of such size as to fit closely the locating pins and the aligning perforations in said cards fitting the locating pins closely with respect to lateral movement of the cards, said cards resting upon the top surface of the table with all of the perforations thereof embracing the locating pins and with the cards overlapping in echelon, thereby to produce the effect of a continuous long record strip in which shrinkage of the cards does not have a cumulative effect and over which card contacting scanning means may slide smoothly in one direction.

6. The combination set forth in claim 5 in which said elongated table is provided with a plurality of relatively large holes, and in which each of said locating pins projects through one of the holes and is movable through a substantial distance, in any direction, and in which means are provided on each pin for clamping the pin to the table in any position to which it may be moved.

7. The combination set forth in claim 5 in which said elongated table is provided with a plurality of relatively large holes and in which each of said pins is provided with a pair of spaced washer-like parts of substantially greater diameter than the diameter of the holes in the table, and in which means are provided on each pin for clamping the pin to the table by pressing said washers respectively against the lower and upper surfaces of the table.

8. An apparatus for scanning premarked record cards comprising an elongated table having tracks at the sides thereof, a plurality of record cards resting by gravity on said table, means for aligning and locating said cards on said table with the cards overlapping in a shingle-like manner, a carriage mounted for movement along said

tracks, and a plurality of scanning instrumentalities mounted on said carriage and cooperable with marks on said cards to produce electrical signals when marks on said cards are scanned.

9. In an apparatus for producing a recording of a musical composition, the combination of a plurality of electrical tone signal generating systems, marked record means for controlling the output of said generating systems, an instrumentation control system having a plurality of predetermined markings operative to effect qualitative and intensity changes in the signal outputs of said generating systems, and means controlled by said first marked record means to render effective a predetermined group of markings on said instrumentation control system.

10. In an apparatus for translating marks upon a card into musical tones, the combination of a card having electrically conductive marks thereon, means movable relative to said card to make contact with the marks thereon and thereby to complete electrical circuits, relays for controlling the effective operation of a generating system, vacuum tubes for operating said relays, means for normally biasing said tubes beyond cutoff, and circuit means including said vacuum tubes and the means for making contact with the marks on the card for controlling said relays.

11. In an apparatus for recording a musical composition having means forming a record of the pitch and duration of the notes of the composition, scanning means cooperable with said record means, a plurality of instrumentalities for producing electrical signals corresponding to the tones to be recorded, a second record and scanning means cooperable therewith, means operated by said first record and its scanning means for selecting the pitch and duration of the tone signals produced by said instrumentalities, and means operated by said second record and its scanning means to select the instrumentality which is to be used to produce the tone signals and to select the tone quality and volume at which such signals are to be recorded.

12. In a music producing apparatus, the combination of a record having manually placed marks indicating the notes to be played, means for scanning the marks on the record, motor means for relatively moving the scanning means and the record at a constant speed, and means for changing the motor speed comprising a plurality of impedances in the motor circuit, a plurality of relays respectively energized by marks having certain locations on the record, and means operated by said relays to increase or decrease the number of said impedance elements effectively in the motor circuit and thereby control its speed of operation.

13. In an apparatus for the rendition of musical compositions, said apparatus including an output system, the combination of a record having a plurality of markings thereon, means for scanning said record comprising photoelectric means arranged to sense the markings on said record and thereby to complete electrical circuits, relay means individually operable upon completion of said electrical circuits, a plurality of tone signal generators, and means operated by said relay means for selectively rendering said generators operative to supply signals to the output system.

14. In an apparatus for automatically producing an orchestral rendition of a musical composition, record means marked to indicate the music to be rendered, a scanning instrumentality cooperable with the markings on said record and more

able relative to the record, musical sound signal producing means controlled by said scanning means, motor means for relatively moving said scanning instrumentality and said record, means for changing the speed of said motor, and marks on said record for controlling the operation of said motor speed changing means.

15. An apparatus for scanning premarked record cards comprising an elongated table having rails at the sides thereof, a plurality of record cards resting by gravity on said table, means for aligning and locating said cards on said table with the cards overlapping in a shingle-like manner, a carriage mounted for movement along said rails, a plurality of scanning instrumentalities mounted on said carriage and cooperable with marks on said cards to produce electrical signals when marks on said cards are scanned, an electric motor for moving said carriage along the rails, and means controlled by marks on the record card for changing the speed of the motor.

16. In an apparatus for recording a musical composition having means forming a record of the pitch and duration of the notes of the composition, scanning means cooperable with said record means, instrumentalities for producing electrical signals corresponding to the tones to be recorded, a second record and scanning means cooperable therewith, means operated by the first record and its scanning means to select the instrumentalities to produce the tones of desired pitch and duration, and means operated by said second record and its scanning means to modify the tone quality of the electrical signals produced by the tone signal producing instrumentalities.

17. In an apparatus for the rendition of musical compositions under the control of marked records, the combination of a generator having an output system including a plurality of series impedance elements, each of said impedance elements having a relay switch connected in parallel therewith, some of said relay switches being normally closed and others being normally open, and means controlled by the marked records for energizing said relay switches, thereby to render one or more of said resistances effective to attenuate the signal supplied through the output system.

18. In an apparatus for controlling the production of a musical selection by selectively combining tone frequency signals from a plurality of sources, a controlling record comprising a plurality of cards of insulating material having imprinted thereon with insulating ink locating linear markings representing the pitch of tones to be produced and locating transverse markings representing the duration of the tones, conducting marks on the cards overlying said markings, circuits including brushes for making contact with the marks, and musical tone signal producing means controlled by said circuits.

19. A sheet of insulating material having imprinted thereon with insulating ink longitudinal and transverse columnar lines representing respectively the pitch and duration of musical tones, said sheet being capable of receiving markings of conductive material, said sheet having a pair of perforations near the ends thereof, one of said perforations being circular and the other of said perforations being elongated, whereby the sheet may expand and contract relative to locating pins extending through the perforations.

20. In an apparatus for controlling a plurality of operations in predetermined sequence and for predetermined intervals of time, a plurality of sheets of insulating material having a surface

capable of receiving pencil marks, said sheets being held in a row with the ends of the sheets overlapping in a shingle-like manner, said sheets bearing conducting marks, and means to sense the marks on the cards comprising a plurality of pairs of brushes, the brushes of a pair being spaced sufficiently close together that they will simultaneously contact a single mark, a control circuit individual to each pair of brushes completed upon contact of its brushes with one of the marks, and means causing relative movement of the sheets and brushes in the direction that the sheets overlap.

21. In an apparatus of the class described, the combination of a support having a card-receiving surface, a plurality of rows of similar accurately spaced locating pins in said support projecting from said surface, and a plurality of cards bearing record markings and located on said surface in rows with the cards in each row overlapping one another in a shingle-like manner, each of the cards having a perforation conforming to the shape and size of one of the pins and having a second perforation elongated in the direction of the row of cards and embracing the next adjacent pin, whereby the cards in a row will be accurately spaced while permitting individual cards to expand and contract.

22. The combination set forth in claim 21 in which the cards are of insulating material and the record markings thereon comprise marks which render the surface of the sheet electrically conductive.

23. The combination set forth in claim 21 in which the record markings on the cards have different light reflecting properties than the surfaces of the cards.

24. In an apparatus for producing music directly from a written record, the combination of a plurality of sources of electrical signals corresponding to musical tones, record cards of insulating material, marks manually placed thereon, means for linearly scanning the cards, including relays energized upon scanning marks in predetermined locations in lineal rows, an output system, means controlled by some of the relays to cause transmission to the output system of tone signals from predetermined sources and to determine the interval of time that such transmission takes place, and means controlled by others of said relays to determine the quality of the tone signals transmitted to the output system.

25. The combination set forth in claim 24 in which others of said relays determine the amplitude of the tone signals transmitted to the output system.

26. A rectangular insulating control card for use in an apparatus for initiating a musical production of orchestral character, said card having a surface capable of receiving conducting marks, insulating markings imprinted on the card to form longitudinal columns representative of the pitches of the tones to be produced and having transverse markings representing the tempo, and conducting marks in the longitudinal column markings and located in positions representing the time of initiation and of length representing the duration of the tones to be produced.

27. In an apparatus of the class described, the combination of an elongated table having track rails at the longitudinal edges thereof, a plurality of rows of equally spaced pins projecting from the upper surface of the table, a plurality of marked cards resting on the surface of the table in overlapping relationship, each of the cards

having a pair of perforations embracing two adjacent pins, and having marks thereon, a carriage mounted on said rails, means to advance the carriage from one end of the table to the other, and means carried by the carriage for sensing the marks on the cards.

28. The combination set forth in claim 27 in which the cards are of insulating material and the marks thereon are of electrically conductive material, and in which the sensing means comprises a plurality of separate electrical circuits each including a pair of brushes positioned to contact the marks on the cards as the carriage advances along the table.
